AUTOMATIC STARTING MEANS FOR PRINTING AND/OR COMPUTING MACHINES

Oscar J. Sundstrand, Rockford, Ill., assignor, by
mesne assignments, to Underwood Elliott Fisher
Company, New York, N. Y., a corporation of
Delaware

Application November 18, 1929, Serial No. 407,929

8 Claims. (Cl. 235—60)

This invention relates to printing and computing machines having a laterally movable paper carriage.

The object of the present invention, generally stated, is to provide automatic means under the control of the paper carriage for causing the machine to perform a cycle of operations.

In doing bookkeeping by means of a cross-tabulating adding and/or subtracting machine there are one or more total positions of the paper carriage. If the carriage supports both a ledger sheet and a statement there may be three total positions.

In most types of machines it is necessary or desirable to take a spacing stroke prior to the printing of a total.

A specific object of the present invention is to obviate the necessity for the operator to depress the motor bar to effect the blank or spacing operation and the total-taking operation. In the present embodiment of the invention, means is provided which is under the control of the paper carriage so that when the paper carriage reaches the position where the spacing stroke should be taken, the spacing stroke is taken automatically, and when the carriage moves from the spacing-stroke position to the total-taking position the machine is again automatically operated to print the total and, if desired, clear the totalizer.

In the accompanying drawings:

Figure 1 is a fragmental right-hand side elevation showing a mechanism embodying the features of my invention. In this view the main rock shaft of the machine is in its initial position.

Fig. 2 is a fragmental rear elevation of certain parts in the same position as shown in Fig. 1.

Fig. 3 is a view similar to Fig. 2, but showing the parts in a different position.

Fig. 4 is a view similar to Fig. 1, but showing the parts in a different position.

Fig. 5 is generally similar to Fig. 1, but shows the parts in the position occupied when the main rock shaft of the machine is at the forward end of its oscillation.

The invention is herein illustrated as embodied in a machine of the type disclosed in French Patent No. 625,678 issued to The Sundstrand Corporation, and in my application Serial No. 118,628, filed June 26, 1926, but it should be understood that the invention is not necessarily restricted to use in machines of this character.

In the embodiment of the invention herein shown there is associated with the paper carriage I (Fig. 4) tabulating means consisting of a control plate 2 which is pivoted at its forward edge

so that it may be tilted on the axis 3, as more fully described in said application Serial No. 118,628. When in its normal or lower position, the rear edge of the control plate 2 rests upon an antifriction roller 4 which is mounted on a housing 5 that is fixed in the frame of the machine below the path of travel of the control plate. In this housing are certain escapement devices, together with devices arranged to control various mechanisms of the machine. The devices referred to coact with stops on the control plate. Said devices and stops are omitted from the present drawings, but are fully disclosed in the before-mentioned French patent and United States application.

The machine is arranged to be driven by an electric motor (not shown) which is controlled by means including a motor bar 6 and a plunger 7 arranged to be depressed by said motor bar. A coiled contractile spring 8 tends to depress the plunger 7 and thus cause the machine to perform a cycle of operations. Said spring is anchored at 9 and is attached to a link 10 which is guided for approximately horizontal movement. The front end of the link 10 is pivoted at 11 to a lever 12 which is pivoted at 13 in the machine frame. The upper end of the lever 12 overlies a pin 14 on the plunger 7. It will be seen that when the spring 8 is free to act, the plunger 7 will be depressed to start the machine. The spring 8 is normally restrained by means to be now described.

An arm 15 is pivoted in the machine frame at 16, and is connected to the link 10 through the medium of a link 17. 18 is a latch lever pivoted on the housing 5 at 19, the lower end of the latch lever being slidable in a slotted guide 20. The lower end of the latch lever is adapted to lie directly behind the upper end of the arm 15 and thus restrain the spring 8 as shown in Fig. 1. The slotted guide 20 prevents the pressure of the arm 15 from laterally displacing the latch lever 18. A coiled contractile spring 21 tends to swing the latch lever into obstructing relation to the arm 15. The action of the spring 21 is limited by engagement of a lug 22 on the latch lever with a stop 23 on the housing 5. A lug 24 on the latch lever extends upwardly into position to be engaged by a pin 25 on the rear edge of the control plate 2. One such pin 25 is located on the control plate in each position corresponding to the positions wherein the machine is to be automatically put through a cycle of operations. It will be seen that when a pin 25 engages the lug 24 the latch lever is swung out of the way of the

arm 15, as shown in Fig. 3, whereupon the spring 8 starts the machine.

Means is provided for restoring the arm 15 to its latched position in order that the machine 5 shall stop at the end of the cycle of operations. The means herein shown for this purpose includes a lever 26 which corresponds to the lever numbered 1057 in my application Serial No. 118, 10 628. The lever 26 is swung forward into the position shown in Fig. 5 during the forward stroke of the main rock shaft 27 of the machine, and is swung rearwardly into the position shown in Fig. 1 in the return stroke of said rock shaft. The lever 26 carries a pin 28 which is arranged to engage a shoulder 29 on the link 10 and thus push said link forward so as to withdraw the lever 12 from the pin 14, and swing the lever 15 into a position in front of the latch lever 18. In the return stroke of the main rock shaft 27, the pin 20 28 moves away from the shoulder 29 and allows the spring 8 to place the arm 15 against the latch lever 18.

As explained in said French patent, at the beginning of the return stroke of the rock shaft 27, 25 the escapement mechanism tilts the control plate 2 upwardly to clear the control devices in the housing 5, whereupon the latch lever 18 springs behind the arm 15, and the carriage moves leftward into the next columnar position. It is possible that the carriage may reach such position 30 before the machine has completed the cycle of operations. If there is a pin 25 corresponding to the next columnar position of the carriage, the latch 18 will be released, thereby starting a new 35 cycle of the machine prior to the completion of the previous cycle. The starting lever 12 should be blocked to prevent such premature starting. I therefore provide the means to be now described. Referring to Fig. 1, 36 is a latch lever pivoted in 40 the machine frame at 31 and adapted to overlie a lug 32 on the lever 12. A coiled contractile spring 33 stretched between the levers 12 and 36 tends to swing the lever 36 into position above the lug 32 and thus prevent the lever 12 from 45 depressing the plunger 7. The latch lever 36 has an arm 34 that underlies a pin 35 on one end of a lever 36 pivoted at 37. A coiled contractile spring 38 tends to swing the lever 36 in the direction to disengage the latch lever 36 from the 50 lug 32. The spring 38 has greater effective strength than the spring 33.

An arm 39 fixed upon the main rock shaft 27 carries a stud 40. In the forward stroke of the rock shaft 27 the stud 40 is carried into engagement with the upper edge 41 of the rear arm of the lever 36, thus swinging the lever in the direction to lift the pin 35 and thus permit the spring 33 to swing the latch lever 36 into effective position above the lug 32, the lug 32 being lowered through the action of the stud 28. The lever 36 is retained in the position just described until near the end of the return stroke of the rock shaft 27 by means of a detent slide 42 which is guided to slide on the studs 43. The forward 60 end of the detent slide 42 carries a squared stud 44 adapted to overlie the rear end of the edge 41, as shown in Fig. 5. When the detent slide 42 is in its rear position the stud 44 overlies a lug 45 on the lever 36 and thus determines the normal 65 position of the lever 36, the latch lever 36 and the plunger 7, as shown in Fig. 4. The detent slide 42 is moved into and out of its effective or forward position by means of an arm 46 pivoted in the machine frame at 47, said arm bearing 70 against the rear end of the detent slide. A

coiled contractile spring 48 tends to swing the arm 46 forward to push the detent slide 42 into effective position. A similar spring 49 stretched between the detent slide and the arm 46 causes the detent slide to follow the arm 46 when the latter is swung rearwardly. On the lower end of the arm 46 is a lug 50 which is arranged to be engaged by the stud 40 near the end of the return stroke of the main rock shaft 27, whereby the arm 46 and the detent slide 42 are restored 10 to their rear position, the lever 36 being thereby released to the action of the spring 38, and the latch lever 36 being thus withdrawn from the lug 32. Consequently, if the control plate 2 is equipped with a pin 25 for the next columnar 15 position, the spring 8 will be allowed to depress the plunger 7 to start the machine.

On the upper end of the plunger 7 is a lug 51 that overlies the pin 35 on the lever 36. When the stud 44 overlies the edge 41, as shown in Fig. 5, the plunger 7 is held elevated, thus preventing the machine from being started by manual depression of the motor bar 6.

It will be seen that the present invention provides a very simple and effective means for automatically causing an adding and/or subtracting machine to perform the cycle of operations required for the "spacing stroke" or for the printing of a total and/or the clearing of the totalizer, or for the printing and/or accumulation of a repeat item.

In the present embodiment of the machine, the power for starting the machine for a cycle of operations is furnished by the spring 8, thus relieving the carriage-moving spring (not shown) of the necessity of supplying such power. The tension of the spring 8 is restored to its proper degree by the motor operating through the lever 26.

I claim as my invention:

1. The combination of a main rock shaft, a laterally movable paper carriage, a starting plunger, a lever arranged to depress said plunger, a link connected to said lever, a spring connected to said link for actuating said lever, a member connected to said link, a latch lever, a spring tending to move said latch lever into position to obstruct the movement of said member, means on the paper carriage to engage said latch lever upon the arrival of the carriage in a certain columnar position and thus withdraw the latch lever from the path of movement of said member, means actuated during the forward stroke of the main rock shaft for moving said link against the influence of the first-mentioned spring, a latch to detain the first lever in the inoperative position to which it is moved by the last-mentioned means, means actuated in the forward stroke of the main rock shaft to permit said latch to become effective, and means actuated in the return stroke of the main rock shaft for withdrawing said latch.

2. The combination of a main rock shaft, a laterally movable paper carriage, starting means, a spring for actuating the starting means, a latch lever to restrain said spring, means on the paper carriage to engage said latch lever upon the arrival of the carriage in a certain columnar position and thus render the latch lever ineffective, means actuated during the forward stroke of the main rock shaft for tensioning the spring, a latch to hold the spring under tension, and means actuated in the return stroke of the main rock shaft for withdrawing said latch.

3. The combination of a main rock shaft, a

- 5 laterally movable paper carriage, starting means, a link arranged to operate the starting means, a spring connected to said link for actuating the starting means, and means effective to disable 10 said link to prevent operation of said starting means, said last mentioned means including a latch lever normally urged into position to defeat operation of said starting means, a lever normally tending to disable said latch lever, 15 an arm on said rock shaft effective to move said last mentioned lever to ineffective position, a detent operable to retain said last mentioned lever in ineffective position, and means on said arm to move said detent out of restraining position with respect to said lever at the conclusion 20 of the return stroke of said rock shaft.
4. In a motor driven computing machine, the combination of a starting element to inaugurate a cycle of operations, a rock shaft, a spring actuated link to initiate movement of said element, 25 a latch to restrain said link, a lever which is spring-actuated to defeat operation of said latch during the first part of a cycle of operations, an arm on said rock shaft to render said lever ineffective intermediate the beginning and ending 30 of a cycle of operations, and means, acting after such operation of the arm, to hold the lever ineffective, said means being disabled by said arm on the completion of the cycle.
5. In a motor driven computing machine, the combination of a starting element to inaugurate a cycle of operations, a spring actuated link tending to operate said starting element, a normally ineffective latch to prevent operation of 35 said spring actuated link, and means including a lever, a detent slide, and a pivoted arm operable to prevent actuation of said starting means by said link prior to the conclusion of a complete cyclic operation of the machine.
6. In a motor driven computing machine, the combination of means tending to start the machine for the performance of a cycle of operations, a latch to restrain said means after the starting of a cycle of operations, a rock shaft, 5 an arm on said rock shaft, a lever normally in position to disable said latch but movable to latch-enabling position, a detent effective to restrain said last mentioned lever in latch-enabling position, and means on said arm effective at the 10 beginning of the performance of a cycle of operations to condition said lever to enable said latch and to actuate said detent at the conclusion of a cycle of operations to permit restoration of said latch to ineffective position. 15
7. A motor-driven computing machine having, in combination, a manually-operable starting element to inaugurate a cycle of operations, means for automatically operating said element, a main rock shaft, and means actuated by said shaft 20 to disable said automatic means during a portion of a cycle, said means also preventing manual operation of said starting element during said portion of a cycle. 25
8. A motor-driven computing machine having, in combination, a manually-operable starting element to inaugurate a cycle of operations, means for automatically operating said element, a main rock shaft, an arm on said shaft, and means controlled by said arm and effective on 30 the forward stroke thereof for disabling said automatic means and for preventing manual operation of said starting element, said means being controlled by said arm and effective near the end of the return stroke of the arm for re-enabling said automatic means and for permitting manual operation of said starting element. 35

OSCAR J. SUNDSTRAND.
